UNITED STATES PATENT OFFICE.

CHARLES T. MILLER, OF MACON, GEORGIA.

ACTUATING DEVICE FOR AUTOMATIC FLUSH-TANK VALVES.

1,251,804.

Specification of Letters Patent.

Patented Jan. 1, 1918.

Application filed June 4, 1917. Serial No. 172,779.

To all whom it may concern:

Be it known that I, CHARLES T. MILLER, a citizen of the United States, residing at Macon, in the county of Bibb and State of Georgia, have invented certain new and useful Improvements in Actuating Devices for Automatic Flush-Tank Valves, of which the following is a specification, reference being had to the accompanying drawings.

10 This invention relates to flush tank valves such as are used in flush tanks of closets, and particularly certain improvements in the devices illustrated in my application for patent filed April 18th, 1917, Serial No. 15 163,064, on automatic flush tank valves.

The general object of this invention is to simplify, cheapen and render more positive in its action, the construction illustrated in my prior application above referred to.

20 And a further object is to provide valve supporting and actuating means which may be assembled and when assembled may be disposed as a unitary combination of parts upon the ordinary overflow pipe, so that an old and worn out flush tank valve may be readily removed with its clamp bracket from the overflow pipe, and this improved construction put in place, without the necessity of tearing out any portion of the tank or re-30 moving or changing the overflow pipe.

A further object of the invention is to provide a device of the construction heretofore described, in which a normally submerged float is used for the purpose of urging the valve to its seat through the intermediary of a manually actuated trip, said trip when released permitting the float to initially rise, this initial rising of the float raising the valve, the fall of the float still 40 further raising the valve until the float has reached a predetermined lowered position, when the valve is released from its engagement with the float and allowed to fall to a closed position.

45 A further object of the invention is to provide a valve lifting means in which the valve is lifted by a float and in which the valve is released by the mere withdrawal of a latch from its engagement with the float, 50 thus reducing the amount of manual operation necessary in order to open the valve.

A further object is to provide means for centering the valve to its seat.

Other objects will appear in the course of 55 the following description.

My invention is illustrated in the accompanying drawings, wherein:—

Figure 1 is a vertical sectional view of a flush tank, partly in elevation, showing my improved valve actuated mechanism applied thereto;

Fig. 2 is a side elevation of the valve actuating mechanism in position when the valve has been initially raised;

Fig. 3 is a like view to Fig. 2 but showing the valve actuating lever descending and just about to release the valve;

Fig. 4 is a section on the line 4—4 of Fig. 1;

Fig. 5 is a front elevation of the valve actuating mechanism.

Referring to these drawings, 10 designates the outlet pipe from a flush tank 11. This outlet pipe is connected by a branch 12 to an overflow pipe 13 in the usual and ordinary manner. The upper end of the pipe 10 is formed with a valve seat 14 of the form usually used with a "Douglas" ball valve. So far all the parts described are old and like those ordinarily found in flush tanks. As before stated, the general object of my invention is to provide a device which will hold the valve to its seat by the pressure of water within the tank, which will lift the valve when the valve has been tripped, hold the valve lifted until the water has run out of the tank, and then cause the closing of the valve. To this end, I provide a valve stem which is designated 15 and which at its lower end carries the valve 16, which is provided on its circumference with a groove or channel 17, having therein the washer 18 coacting with the valve seat 14. The outer wall of the channel 17 is extended sufficiently far over as to hold the washer firmly and prevent its being flattened or otherwise deformed from its proper shape.

The valve stem 15 is widened at its middle portion and longitudinally slotted, as 19, to form a yoke and at its upper end the valve stem is reduced in diameter and extended through a guide eye 20 formed upon a guide bracket 21. This guide bracket at its lower end is provided with an inwardly deflected arm 22 having a laterally extending vertically slotted guide 23, in which the yoke of the valve stem 15 fits and slides. The guide bracket 21 is formed adjacent its lower end with an enlarged 110

portion 24, from which extends a shank 25 received in a socket 26 formed upon the clamp 27. This clamp 27 is split in the usual manner of clamps of this character and is held to clamp upon the overflow pipe 13 in any suitable manner. A set screw 28 passes through the wall of the socket 26 and engages the shank 25. I do not wish to be limited to this construction, however, as any other manner of connecting the member 24 of the bracket 21 to the clamp 27 may be used.

Rotatably mounted in the upper end of the yoke 15^a is a roller 29, and pivotally mounted upon a stud 30 projecting from the member 24 is a cam, designated generally 31. This cam is preferably formed of a casting and has the shape illustrated best in Fig. 3, the cam being skeletal in form so as to make it lighter and reduce the amount of material used. The upper edge face of the cam is upwardly curved as at 32 and the forward edge face is downwardly and inwardly curved as at 33, then extended straight outward, as at 34 to form a nose. The lower edge of this nose and the cam extends rearward in an approximately horizontal line, as at 35. Attached to the cam is the outwardly projecting rod 36, which carries upon it the float 37. This rod 36 may be cast with the cam or attached thereto in any suitable manner and the float may be attached to the rod in any suitable manner.

Swingingly mounted upon the yoke 15^a, intermediate its ends, is a latch 38. This latch is approximately U-shaped to provide two legs 39 and a cross bar 40, the extremities of which are perforated as at 41. The latch is pivoted through the legs at 42 to the yoke, the legs embracing the side bars of the yoke 15^a and the latch normally hanging in an approximately vertical position with its cross bar extending across the slot 19. The latch is operatively connected by means of a flexible metallic connection 43^a to a trip handle 43, which may be of any suitable character. When this trip handle is shifted in either direction, it will cause the trip to be shifted from its normal position into the position shown in Fig. 1.

The operation of the mechanism so far described is as follows:—Normally the valve 16 rests upon the seat 14 and outlet from the tank is closed. At this time, the under face 35 of the nose 34 rests upon the cross bar 40. The float 37 is entirely submerged and the buoyancy of the float tends to move the float upward and, of course, this upward pressure on the float forces the nose downward upon the cross bar 40 and thus holds the valve to its seat by the upward pressure on the float. When it is desired to flush the closet, the handle 42 is rotated, which retracts the latch 38, as illustrated in dotted lines in Fig. 1. As soon as the latch is re-

tracted, the float 37 moves upward and as soon as the cam 31 begins to rotate, its curved face 32 will engage beneath the roller 29 and as the cam rotates, the yoke 15^a will ride up upon the cam thus opening the valve. As soon as the handle 43 is released, the latch 38 will swing inward, so that when the yoke 15^a has been lifted a predetermined amount by the cam, the latch will swing inward to a position above the nose 34, as illustrated in Fig. 2. At this time the float 37 has reached its uppermost position and as the water is running out of the tank, the float will commence to descend and, under these circumstances, the nose 34 will lift upward upon the cross bar 40 of the latch, still further lifting the yoke 15^a, the valve stem 15 and the valve 16. As the float 37 nears the bottom of the tank, the nose 34 will slip from beneath the cross bar 40 of the latch (see Fig. 3) and as soon as this has occurred, the valve drops of its own weight. As soon as the water rises in the tank, due to the closing of the valve, the float 37 will rise until eventually the nose 34 will again act to bear upon the upper edge of the cross bar 40, again holding and urging the valve to its seat and locking the float 37 from any further upward movement until the latch 38 is released.

Where this device is to be installed in a flush tank already equipped with an overflow pipe, and it is only desired to substitute for the "Douglas" valve, the valve construction which I have described, no parts, other than those previously described, are intended to be used, but where this valve is intended to be applied to an overflow pipe when the overflow pipe, flush tank, etc., are initially described, then I will provide a cap 44 for the upper end of the overflow pipe, this cap being mounted upon a lever 45, in turn pivotally supported upon a bracket 46 extending upward from the guide member, this lever having a perforation 47 in its end through which an extension of the stem of the valve passes, this extension being provided with a nut or stop 48. Now when the valve falls, this nut or stop 48 engages with the lever 45 and raises the cap 44 so that the overflow pipe acts in its usual manner, but as soon as the valve is raised by the operation of the actuating handle, in the manner heretofore described, the cap 44 is allowed to lower on the upper end of the overflow pipe and closes the upper end of this overflow pipe, so as to prevent the gurgling noise which usually accompanies the outflow of water from a flush tank and is due to the downward passage of air into the upper end of the overflow pipe, the air being drawn in by the water passing downward through the flush pipe.

It will be seen that in my construction the valve stem is guided by the guide member

21, so that the valve will always descend in proper alinement with the valve seat, so as to seat properly thereon. It will further be seen that the valve is held to its seat by the 5 upward pressure due to the buoyancy of the float and this is a very important and vital feature of my invention, and it is again to be noted that it is not necessary, in my construction, to manually lift the valve from 10 its seat by a relatively long pull upon the actuating chain, handle, lever, or other device, as it is in the majority of flush tanks, but that a very slight movement of the actuating handle will trip the latch and that 15 thereafter the operation of the parts is entirely automatic, and the valve will rise to its full extent and will be held in its raised position until the greater portion of water has been discharged from the flush tank. 20 Where the valve itself is lifted by a manually actuated device, it sometimes occurs that only a very slight pull is given to the actuating cord or handle and then the valve rises and almost immediately closes, without 25 flushing the tank. With this construction, however, the slightest movement of the latch releases it and the valve is immediately opened to its full extent and then closes when the water has descended to a predetermined level. This construction is very 30 simple, it may be cheaply made, and it is obvious that it may be very readily put in place in ordinary flush tanks having a vertically extending outlet pipe, even though 35 that outlet pipe be not connected to the flush pipe, as illustrated. It is only necessary to remove the old valve mechanism and then dispose the collar 27 upon the overflow pipe with the valve parts mounted thereon all 40 ready for operation.

The outlet valves ordinarily used in flush tanks for the purpose of controlling the outlet of water are very liable to leak. They are simply held down in place by the pressure of the water and by no positive means, as far as is known to me. Furthermore, these valves, as has been stated before, require a relatively long actuating movement and very often these valves are not fully 45 opened. Furthermore, the valve ordinarily employed in flush tanks is what is known as the "Douglas ball or floating valve" and these valves are made of an upper portion of relatively stiff rubber and a lower portion 50 of relatively soft rubber and, as a consequence, these valves very soon get out of shape and become laterally expanded so that they do not fit the valve seat and indeed oftentimes contact with the wall of the flush 55 tank, thus preventing the easy movement of the valve. Furthermore these hollow float valves, unless they are drawn to their full distance from the valve seat, are very liable 60 to be sucked back upon the seat by the initial outlet of water from the flush tank, and

even if they are so drawn away from the seat yet when the valve moves downward within an inch or so of the valve seat, the suction of the water will draw the valve to its seat, thus preventing the full discharge of water 70 from the tank, which is absolutely undesirable. It will be seen that these objections are obviated by the construction which I have provided. The object of having the socket 26 on the clamp 27 is to permit the 75 member 24 to be adjusted, so as to adjust the guide, with its guide openings 20 and 23, in alinement with the axis of the valve seat.

Having described my invention, what I claim is:—

1. A flush tank including a valve, a valve seat, a vertically disposed member disposed in the tank, a valve stem extending from the valve, a valve stem guide carried by said member, a float operated valve lifting lever 85 operatively mounted upon said member, and a latch normally hindering the operation of the valve lifting lever, but shiftable out of engagement with the lever to permit the raising of the valve. 90

2. In a flush tank, a valve and valve stem, a vertically disposed member, a vertically extending guide carried by said member and through which the stem passes, a valve lifting lever operatively mounted upon said 95 member and operatively engaging the valve stem to lift it upon a movement of the lever under the action of its float, and a latch operatively mounted upon the valve stem and normally hindering the operation of 100 said lever, but shiftable out of operative engagement with the lever to permit the lever to lift the valve.

3. In a flush tank, a valve seat and valve, a lever pivoted intermediate its ends, a float 105 connected to one end of the lever and normally submerged, a cam shaped member mounted upon the opposite end of the lever and operatively engaging the valve stem to cause the lifting of the valve stem as the 110 lever moves under the actuation of its float, and means normally hindering the movement of the lever under the action of its float, but shiftable to permit said movement.

4. In a flush tank, a valve seat, a valve, 115 a valve stem extending upward from the seat, a roller mounted on the valve stem, an operating lever pivoted intermediate its ends and carrying a float at its outer end, the inner end of the member being formed 120 to provide a curved upper edge face engaging with said roller to cause the roller to ride up on said curved edge face as the lever moves upward under the action of the float to thereby lift the valve, and means normally hindering the movement of the lever under the action of its float but shiftable 125 out of operative engagement with the lever to permit said movement.

5. In a flush tank, a valve seat, a valve 130

therefor having a valve stem, the stem being provided with a roller, a lever pivotally supported below the roller and to one side of the valve stem, said lever at its inner end being extended upward from a point nearly coincident with its pivotal axis and forward toward the valve stem, then extended rearward and downward in a curve to form a curved cam, the outer end of the lever being provided with a float, said curved face when the lever moves upward engaging beneath the roller to shift the valve stem upward, and means normally preventing the operation of the lever under the action of its float but shiftable to permit said operation.

6. In a flush tank, a valve seat and a valve, a lever pivoted intermediate its ends and carrying a float at its outer extremity, a valve stem extending upward from the valve and carrying a roller, the inner end of the lever being formed to provide a nose projecting beyond the valve stem, and an upwardly extending portion formed with a rearwardly curved face adapted to engage with the roller as the outer end of the lever moves upward under the action of the float, a latch swingingly mounted upon the valve stem and normally engaging beneath the nose of the lever whereby the lever acts to hold the valve to its seat, said latch being shiftable out of such a position to thereby release the lever and permit it to rotate under the action of the float to thereby initially engage the roller and lift the valve stem, the latch then swinging back to a position above the nose of the lever whereby when the float end of the lever falls, the valve stem and valve will be further lifted until the nose of the lever disengages from the latch to permit the valve to fall to its closed position.

7. As an article of manufacture, a valve and a valve operating mechanism for flush tanks comprising a clamping collar, a guide operatively mounted upon the clamping collar and having terminal portions formed with alined vertically disposed eyes, a valve stem shiftable through said eyes and carrying a valve, a lever operatively supported upon the clamping collar and having a float at one end, the other end of said lever extending adjacent the valve stem, and means normally preventing a movement of the lever under the action of its float, but releas-

able to permit said movement, and means carried by the valve stem engaged by the lever on its upward movement to thereby cause the lifting of the valve.

8. As an article of manufacture, a valve and a valve operating mechanism for flush tanks comprising a clamping collar, a guide operatively mounted upon the clamping collar and having terminal portions formed with alined vertically disposed eyes, a valve stem shiftable through said eyes and carrying a valve, a lever operatively supported upon the clamping collar and having a float at one end, the other end of said lever extending adjacent the valve stem, and means normally preventing a movement of the lever under the action of its float, but releasable to permit said movement, and means carried by the valve stem engaged by the lever on its upward movement to thereby cause the lifting of the valve, said lever acting upon the descent of its float end to still further lift the valve and releasing its engagement with the valve stem when the float has descended to a predetermined point.

9. As an article of manufacture, a valve and valve actuating means therefor comprising a clamp, a member adjustably mounted on the clamp and having a vertically extending guide rod, the upper and lower ends of the guide rod being laterally deflected and formed with eyes in alinement with each other, a valve, a valve stem connected thereto and passing through said eyes and guided thereby, the valve stem being slotted, a roller mounted on the upper portion of the valve stem, a swinging latch mounted upon the valve stem and extending across said slot, and a lever pivotally mounted upon said member and having a float at its outer end, that end of the lever adjacent the valve stem having a nose and an upwardly extending portion formed to provide a curved cam face engageable with said roller as the lever moves upward under the action of the float to thereby lift the valve, the latch normally engaging beneath the nose of the lever but being shiftable out of such engagement.

In testimony whereof I hereunto affix my signature in the presence of two witnesses.
